BEVERAGE CUP

Valentino Pera, Pinole, Calif., assignor of one-half to Orsela Lucia Pera, Pinole, Calif.

Application May 6, 1941, Serial No. 392,061

3 Claims. (Cl. 65—13)

The invention relates to a container such as a cup or mug or stein from which beverages are to be drunk.

An object of the invention is to provide a beverage container of the character described having means for facilitating a suction removal of its contents in lieu of drinking from the lip thereof.

Another object is to provide for the progressive removal of the beverage from the bottom thereof, whereby to avoid the drinking of any froth or scum on the beverage.

A more specific object is to provide a cup of the type described having a suction well provided in an accessory portion of the container which may also comprise a handle for the container.

The invention possesses other objects and features of advantage, some of which, with the foregoing, will be set forth or be apparent in the following description of a preferred embodiment thereof, and in the accompanying drawing, in which,

Figure 1 is a perspective view of a stein-like mug embodying the features of the invention, and supported in a person's hand by its handle for the removal of its contents through a suction straw disposed in its suction well.

Figure 2 is an elevation of the mug with the structure thereof shown in section at the suction well.

Figure 3 is a fragmentary section at the line 3—3 in Figure 2.

Figure 4 is a plan view of the mug.

As particularly illustrated, the features of present invention are incorporated in the structure of a mug 6 or the like having a receptacle portion 7 of cylindrical form provided with a handle extending integrally therefrom. Essentially, a lateral receptacle extension 8 provides a suction passage 9 connected with the bottom of the receptacle cavity 11, with the passage 9 extending at least to the plane of the lip of the mug. Conveniently, and as shown, the extension 8 comprises part of the mug handle.

While the passage 9 may be utilized directly as a suction passage for removing the receptacle contents by the application of the drinker's mouth to the upper passage end at the upper end of the tubular handle portion 8, it will generally be preferable for sanitary reasons, that a drinker utilize an individual tube applied through the passage 9 for removing the mug contents by suction. Accordingly, the extension 8 is so formed that the suction passage 9 therethrough may freely receive a suitable suction tube 12. Since rigid suction tubes of glass or paper are usually straight, and

a flexible tube of rubber or the like may be straightened in a straight bore, the passage 9 is preferably straight for receiving either a rigid or flexible tube, it being recalled that straight suction tubes are frequently referred to as "straws."

In the present structure, the handle portion 8 provides a straight passage 9, extends obliquely upwardly from the receptacle bottom, and may be connected to the receptacle near its top end by means of an integral handle portion 13. In this manner, the handle portions 8 and 13 cooperate with the opposed mug side to provide a handle loop for receiving fingers of a supporting hand. With the resulting disposition of the discharge end of the passage 9 at a point laterally spaced from the receptacle, the drinker's face need not be directly over the receptacle as when a suction tube is applied within the receptacle.

While I have disclosed the provision of the passage 9 in a lateral mug extension 8 which comprises part of the mug handle, it will be understood that such an extension is not necessarily part of a handle. Also, the angularity of the extension with respect to the adjacent mug side may be varied; in fact, the angle between the extension and the opposed mug side portion may be zero whereby the extension is parallel to the mug side and cross-sections taken at different heights along the wall may be as the section of Figure 3.

For facilitating the removal of the mug contents through a tube 12 disposed in the passage 9, the receptacle bottom portion 14 may be provided with a depression 15 opposite the end of the passage 9 and arranged to facilitate the flow of liquid from the receptacle cavity into the tube or straw 12. As particularly shown, the lowermost corner of the suction tube 12 is arranged to rest upon an undepressed bottom portion adjacent the depression 15.

The described mug structure may be formed of glass or ceramic ware or a plastic or a metal as may be desired. It will of course be obvious that a precise handle outline for providing the present straight suction passage 9 is generally immaterial.

While of general utility, the present mug structure has been particularly designed to facilitate the drinking therefrom of liquids which have frothy or unpalatable top portions or carry fruit pieces or other decorations above the liquid, such liquids including medicinal preparations, egg-noggs and other whipped beverages, malt liquors, chocolate drinks, etc. Since the liquid to be

served would be originally placed in the cup from the top of its cavity 11, the passage 9 will be free of froth or scum, and the insertion of a straw 12 therein may not cause a clogging of the straw bore as might occur if the straw is lowered directly into the liquid in the cup cavity. It will thus be understood that the present mug structure is useful both in the hospital and the home and at refreshment counters.

From the foregoing description taken in connection with the accompanying drawing, the advantages of the construction and method of use will be readily understood by those skilled in the art to which the invention appertains. While I have described the features and the principle use of an arrangement which I now consider to be a preferred embodiment of my invention, I desire to have it understood that the showing is primarily illustrative, and that such changes may be made, when desired, as fall within the scope of the following claims.

I claim:

1. In a mug or the like, a body providing a liquid receptacle and a lateral tubular extension providing a uniform straight passage connected with the receptacle space solely at a receptacle side point adjacent the receptacle bottom, and a straight and laterally rigid suction tube removably disposed in said passage and having its lower end supposedly engaging the receptacle bottom and its upper end exposed beyond the top of the passage for the application of a person's mouth thereto for effecting the suction removal of the receptacle contents, the receptacle bottom opposite the lower tube end being vertically stepped with the higher bottom portion thereof supportingly engaging the tube and the lower bottom

portion thereat extending laterally beyond the tube end to provide for a free liquid flow along the bottom and beneath the tube into its said end.

- 5 2. In a mug or the like, a body providing a liquid receptacle and a lateral tubular extension providing a passage extending upwardly from the receptacle bottom to at least its top level, a suction tube removably disposed in said passage 10 and having its lower end supposedly engaging the receptacle bottom and its upper end exposed beyond the top of the passage for the sucking application of a person's mouth thereto, the receptacle bottom opposite the lower tube end being vertically stepped with the higher bottom portion thereat supportingly engaging the tube and the lower bottom portion thereof extending laterally beyond the tube end to provide for a free liquid flow beneath the tube into its said end. 15 3. In a mug or the like, a body providing a liquid receptacle, and a lateral extension of the body providing a passage extending upwardly from the bottom of the mug receptacle to at least the plane of the receptacle top, a suction tube 20 replaceably disposed in said passage with its lower end supposedly engaging the receptacle bottom while its upper end is exposed beyond the top of the passage for the suction removal of the receptacle contents through the tube, and means 25 facilitating the flow of liquid from the receptacle bottom to the intake end of the installed tube, said means comprising the formation of the receptacle bottom with a depressed portion disposed to underlie less than all of the lower end 30 of the tube and to extend laterally from beneath the tube.

VALENTINO PERA.
